UNITED STATES PATENT OFFICE.

FREDERICK L. ROWLEY, OF ST. PAUL, MINNESOTA.

CROSSHEAD PULLER.

Application filed January 13, 1926. Serial No. 80,912.

My invention relates to crosshead puller wherein it is desired to pull the crosshead from the piston rod in a locomotive. It is very apparent that from time to time it is necessary to make such changes and to remove the crosshead from the piston rod so that an engine can be repaired; and it is important that this be done in the shortest possible time so that the engine will not be laid up longer than is necessary and without taking the engine all apart at the crosshead connection.

A feature of the invention resides in a crosshead puller which is provided with a floating crosshead pin so as to prevent strain on the back wall of the crosshead in applying sufficient force to remove the piston rod therefrom.

It is also a feature of the invention to provide a double puller working from both ends forcing the piston rod out of the crosshead by pressure against the end of the piston rod, while force is applied against the cross head to push the same off of the piston rod at the same time that the force is exerted against the inner end of the piston rod. This is an important feature of my invention.

My invention includes adjustable connecting rods or side arms which connect the ends of the crosshead puller together in a manner so that an operating member is held extending through the crosshead transversely and held approximately in a floating nature in relation to the crosshead so that no strain is exerted against the crosshead hole, and to permit the adjusting of my crosshead puller to various sized locomotives so that the adjustments provided by my crosshead puller are sufficient to take in a large scope of locomotives, making my device very practical for such use. The majority of locomotives have a uniform construction or comparatively so in relation to the crosshead pin hole and the piston rod so that my adjustable crosshead puller is readily adaptable to any of these makes of locomotives.

A feature of my invention resides in a crosshead puller and connecting parts which are machined in a manner to fit together properly and so as to prevent the putting together of these parts incorrectly, thereby making a very simple device which can be operated readily. It is a feature that my crosshead puller can be operated from either end or from both ends at the same time by

applying power to the screw members in each end. This is accomplished by large wrenches or other suitable means of applying power to the screw members which applies pressure to the crosshead and piston rod in a manner to separate the same. I include a thrust ball bearing or other suitable bearing which eliminates friction between the end of the collar which works against the inner surface of the crosshead or boss portion of the crosshead projecting toward the piston rod and which receives the piston rod therein. The bearing member permits the collar to be turned more readily. It is apparent that my collar member can be used either with or without the thrust ball bearing and that the bearings may be of a ball nature or roller bearing so as to eliminate friction to a large degree.

Heretofore it has been quite commonly practised in the removing of crossheads from piston rods to rely on the back wall of the crosshead pin hole, which is the weakest part of the crosshead, to withstand all the strain necessary to pull the piston rod from the crosshead. By my floating crosshead pin which is supported by the side connecting arms or links I entirely overcome this method of removing the piston rod and transmit the strain to the connectors and the floating pin extending through the crosshead pin hole. With my crosshead puller no cracking in crossheads will be a result of removing the piston rod, as is often the case with the old method used heretofore in so far as I know. My method also overcomes the necessity of reaming crosshead pin holes on account of being stretched in the removal of the crosshead from the piston rod by the old method. My crosshead puller is harnessed around the crosshead in a manner to take all the strain of removing or pulling the crosshead from the piston rod.

A very important feature of my crosshead puller resides in the pin member which extends through the end of the crosshead and is threaded into the floating pin in a manner so as to transmit pressure against the inner end of the piston rod to force the same out of the crosshead when pressure is applied to the pin. When this pin is screwed up tightly against the piston rod, if the piston rod does not give under the pressure of the pin a blow with a sledge hammer against the outer end of the pin or head of the same will often times jar the piston rod free of

the crosshead. My crosshead puller is of extreme importance in the use of locomotives at this time because of the increase in the size of the locomotives and of the larger crossheads and piston rods which are necessary with these high powered locomotives that are now being used by railroads.

These features together with other details of construction and particular arrangement 10 of the parts will be more clearly and fully set forth in the specification and claims.

In the drawings forming part of this specification:

Figure 1 is a side view of my crosshead 15 puller as it would appear attached to the side of a crosshead of a locomotive, a part of which is broken away.

Figure 2 is a plan view of my crosshead puller attached to a crosshead of a locomotive, partly illustrated in cross-section.

Figure 3 is an end view along the line 3—3 of Figure 1.

Figure 4 is a detail of one of the connecting links or arms.

25 Figure 5 is a detail of the end stop pin.

Figure 6 is a detail of the crosshead floating pin removed from the same.

Figure 7 shows the piston rod collar with the parts of the same separated slightly to 30 show that the parts are separable from each other.

In the drawings my cross head puller is provided with a collar portion A and a crosshead floating pin portion B which is 35 adapted to extend through the crosshead pin hole 10 in a manner so as to be held practically in a floating position through the crosshead C so that the piston rod D may be readily removed without causing any strain 40 to be exerted against the crosshead C at a point where it would be very undesirable, and as has been done heretofore with some methods for removing the piston rod from the same.

45 My crosshead puller is designed to be used with locomotives and it is quite desirable that the piston rods D be removed from time to time for various reasons from the crosshead C. My crosshead puller is designed to provide a powerful means of disengaging or separating the crosshead from the piston rod and I provide a collar A which is designed with the upper portion 12 which is separable from the lower portion 13 in a manner so that the collar A can be positioned about the piston rod D and secured together or be separated so as to be removed from the rod. The portions 12 and 13 are formed with an inter-locking edge 50 which is provided with rabbeted portions 14 which interlock so as to hold the parts 12 and 13 in perfect alinement and properly connected together. This is important in the collar construction because the inner surface 55 of the collar is threaded at 15.

The collar portions 12 and 13 are held together by the pins 16 which are carried by the lower portion 13 and the wedge keys 17 which extend through slots in the pin 16 in a manner to lock the portions 12 and 13 rigidly and securely together. Dowel pins 18 are also provided to hold the parts 12 and 13 in alinement so that when the parts 12 and 13 of the collar A are secured together, the collar A is as if it were one piece 75 in operation.

The rigid and accurate construction of the collar A permits the thread 15 to function in a manner to engage the thread 20 on the collar nut 21 which is formed in two half portions having a suitable rabbeted edge 14 and similar dowel pins 18 which hold the half parts in perfect alinement so that the collar nut is adapted to thread perfectly 80 into the collar A.

The collar A is provided with projecting lugs 22 which are formed with a semi-circular end 23 on one side over which the yoke 24 of the connecting arms or links 25 engage. These links 25 are constructed so as to be positioned in a manner to engage the lugs 22 on either side of the collar A. The surface 23 of these lugs is angled inwardly to the point 26 so that the yokes 24 will have a tendency to draw inwardly on the lugs rather than slipping off of the same when the crosshead puller is in operation. Each of the lugs 25 is threaded at 28 in a manner so as to make an adjustable connecting means on either side of the collar A.

The threaded end 28 of the links or arms 25 is adapted to extend through the slots 29 formed in the ends 30 of the crosshead pin 31. The crosshead pin 31 is shaped in a manner so as to extend through the crosshead pin hole 10 freely and to provide a floating connection for the adjustable ends of the rods or links 25. By means of suitable nuts 32 which bear against the plates 33 the links 25 are adjusted in a manner so as to cause the plates 33 to bear against the flattened side 34 of the lugs 30 of the crosshead pin 31. Each of the plates 33 is provided with a tongue 35 which fits in a similar groove formed in the flattened surface 34 of the lugs 30 so as to hold the plates firmly against the lugs 30 of the pin.

The crosshead C is formed with an opening 36 which extends through the web 37 of the same and which is of ordinary construction in the make up of the crosshead for a locomotive. This opening 36 extends through the crosshead and into the shank 38 of the crosshead to connect with the tapered piston rod receiving opening 39 formed in the shank or projecting boss of the crosshead C. The piston rod D is tapered at 40 in a manner so as to fit into the opening 39 and is held in the ordinary manner therein, by a pin wedge not illus-

trated in the drawings and of ordinary well known construction. The connecting rod D must be held absolutely tight within the crosshead C and therefore the tapered end 40 of the piston rod is wedged very securely into the tapered opening 39 so that it is in position to disengage the same without considerable force against the crosshead C and the rod D under ordinary conditions. In fact, some of these piston rods D are so tightly connected in the crosshead that the web 37, which is practically the weakest point, adjacent the crosshead pin hole 10 of the crosshead is cracked when the piston rods D are being removed by old methods which I have seen heretofore.

In my method I provide a piston rod end wedge pin 42 which is formed with a nut head 43 on one end and is formed with threads 44 along the major portion of the same at the end opposite the head 43. This wedge pin is adapted to extend through the opening 36 in the crosshead and is threaded at 45 through the crosshead floating pin 31. The threaded end 44 of the pin 42 is provided with a projecting centering point 46 which is adapted to engage in the center recess of the tapered end 40 of the piston rod D.

The construction of my crosshead puller is very simple so that in use the collar A may be readily assembled around the piston rod D adjacent the boss 38 of the crosshead C, and the collar nut 21 inserted within the same and turned up against the thrust ball-bearing 48 which is inserted between the end of the collar 21 and the faced end 49 of the boss 38 on the crosshead C. The adjustable connecting arms or links 25 are then attached to the lugs 22 and inserted through the pin 31 which has been placed to extend freely through the opening 10 of the crosshead C, and by adjusting the nuts 32 after the wedge pin 42 has been set up against the end of the piston rod D, as illustrated in Figures 1 and 2, the nuts 32 are drawn tight enough to hold the crosshead floating pin 31 extending freely through the opening 10 and without engaging or bearing against the sides of the same excepting as to support the weight of the pin and the ends of the links 25. In fact, the supporting of the pin 31 through the opening 10 of the crosshead C is only temporary until the wedge pin 42 is drawn tight against the end of the piston rod D, and then the pin 31 extends practically in a floating position through the opening 10.

After the connecting links 25 have been adjusted to the desired length to hold the pin 31 centrally through the opening 10 and to draw the thrust bearing 48 up against the face 49 of the boss 38 of the crosshead C, by means of suitable wrenches at 42 the collar 21 can be operated to bring pressure

against the end of the piston rod D and at the same time against the face 49 of the crosshead C, thereby forcing under extreme pressure the piston rod D out of the recess 39. If for any reason the piston rod D does not readily respond to this operation when the collar 21 and the wedge pin 42 are drawn tight, then by a sledge hammer blow against the head 43 of the pin 42, it will be found that the piston rod D will readily disengage from the crosshead C. It is not often that it is necessary to strike the pin 42, for as a rule the crosshead C will be readily pulled from the piston rods D. The adjustment of the links or arms 25 permit my puller to be readily adjusted to different sized locomotives and crossheads and the operation is very effective being of a simple nature so that the crosshead puller can be quickly attached and removed. In fact, I have found that my crosshead puller operates so effectively as to take only a very short time to completely remove the crosshead from the piston rod. In my crosshead puller no pressure is exerted against the weak portion of the crosshead, but rather to the contrary the pressure is exerted and directed to the body and face 49 of the crosshead so as to operate with such force as to readily separate the piston rod from the same. In operation the connecting rods 25 are held on the lugs 22 by the inclined surface 26 so that they will not separate from the same, and I provide a suitable handle E on the upper portion 12 of the collar A so that the collar can be lifted in separating it from the rod D. The thrust ball-bearing or roller bearing which may be used, such as 48, eliminates the friction in the turning of the collar 21 and thus permits my crosshead puller to operate very freely, while the pin 42 provides the necessary stop for engaging against the end of the piston rod D with the centering point 46 holding the pin centrally in relation to the piston rod.

While I have illustrated a particular formation and construction of my crosshead puller I desire to have it understood that the illustration is only suggestive of a means of carrying out my invention and that the same can be modified and the parts so arranged as to fulfill the functions herein set forth and within the scope of the following claims.

I claim:

1. A crosshead puller having means adapted to be associated with a crosshead and piston rod in a manner to exert pressure against the extreme end of the piston rod to force the same out of the crosshead, bearing members pressing against the inner end of the crosshead, said means comprising a floating pin member adapted to extend through the crosshead and connecting rods

- extending on either side of the pin member to connect the same with said bearing members.
2. A crosshead puller including, a collar member adapted to extend about the piston rod of a locomotive adjacent the crosshead, a pin adapted to extend through the crosshead pin hole, connecting means adapted to connect said pin with said collar in a manner to hold said pin in a floating relation with the pin hole in the crosshead and means coating with said pin to permit pressure to be exerted against the end of the piston rod without stretching the crosshead at the pin hole.
3. A piston rod remover including, means adapted to engage one end of the crosshead of a locomotive, a floating pin adapted to extend through the crosshead, means connecting said pin with the means adapted to engage one end of the crosshead, and means adapted to extend through said floating pin to transmit pressure against the end of the piston rod in the crosshead.
4. A crosshead and piston separating means comprising a member adapted to encircle the piston rod, a collar threaded into said member and adapted to bear against the projecting portion of a crosshead which carries the piston rod, a cross head pin adapted to extend through the crosshead pin hole, adjustable connecting links adapted to connect the crosshead pin with said collar in a manner to hold the crosshead pin floating within the crosshead pin hole, and a piston rod wedge pin threaded into said crosshead pin in a manner to bear against the inner end of the piston rod to force the same out of the crosshead.
5. A crosshead puller for locomotives including, means for engaging about the piston rod, anti-friction means for bearing against the crosshead, connecting means adapted to connect said engaging means extending about said piston rod with the end of said piston rod whereby when pressure is exerted against the end of the crosshead adjacent the piston rod, the piston rod and crosshead may be separated.
6. A crosshead puller for locomotives comprising a separable collar adapted to extend about the piston rod, a separable collar adapted to thread into said first separable collar and extend in a manner to bear against the inner end of a crosshead, wedge means and means for connecting said first collar to said wedge means adjustable in a manner to cause the crosshead to be pulled away from the piston rod when said second threaded collar is rotated against the crosshead.

7. In a device of the class described including, a collar adapted to extend about a piston rod, a collar nut adapted to be threaded into said collar, a crosshead pin extending through the crosshead, connecting means adapted to connect said collar with said crosshead pin, said connecting means causing the crosshead pin to have a floating relation through the crosshead and means bearing against the end of the piston rod carried by said crosshead pin to cause a crosshead to be pulled from the piston rod when said collar nut is rotated against the crosshead.

8. A crosshead puller including, a pin adapted to extend through the crosshead, means for holding said pin in floating relation through the crosshead, and means adapted to connect said holding means with the end of the crosshead opposite the end of the piston rod to bear against the crosshead in a manner so as to pull the crosshead from the piston rod.

9. A crosshead and piston separating means including, a split collar member adapted to extend about the piston rod, a collar nut adapted to be threaded into said collar member, connecting links, lugs extending from said collar member adapted to receive one end of said links, a crosshead pin adapted to extend through the crosshead pin hole, slotted ends formed in said pin for receiving the ends of said connecting links and an adjustable wedge pin threaded through said crosshead pin in a manner to extend and bear against the piston rod so that when the adjustable screw pin and the collar nut are rotated the crosshead and piston rod will be separated from each other.

10. A crosshead and piston separating device including, means adapted to bear against the end of the piston rod, and means connected to said first mentioned means adapted to bear against the boss of the crosshead to hold the piston rod whereby when pressure is exerted against the piston rod and crosshead by both said means they will be separated one from the other.

11. A crosshead and piston separating device for locomotives including, means adapted to engage against the portion of the crosshead in which the piston rod is secured, and means connected to said first mentioned means adapted to bear against the end of the piston rod whereby pressure directed against the end of the piston rod inside the crosshead and pressure directed against the end of the crosshead holding the piston rod outside of the same will separate the piston rod and crosshead.

FREDERICK I. ROWLEY.
